Conn., a corporation of New York

Application June 30, 1949, Serial No. 102,207

11 Claims. (Cl. 118—223)

1

This invention relates to gummed tape dispensers, and particularly to adjustable brush moistener mechanism for moistening the tape as it is dispensed.

In gummed tape dispensers, particularly those designed for the rapid dispensing of tape for sealing fibre shipping cases, the moistening of the dry glue on the tape must be controlled with great precision. The tapes used are often of substantial width and long lengths dispensed at comparatively high speeds. If exactly the right amount of water is not applied to the tape, unsatisfactory results will follow. If too little water is applied, the glue will not be sufficiently softened and the water may be applied only in streaks so that parts of the glue will not adhere at all. If too much water is applied, the glue will be reduced to a slippery condition, rather than the tacky condition which is necessary for satisfactory adhesion. If so much water has been applied that the glue is flooded, then when the packer tries to rub the tape over the box seams, it will not adhere properly, as conditions for proper adhesion between the tape and box cannot be brought about until after the packer has stopped rubbing the tape down. In either instance the box will be improperly sealed, such a condition, however, probably not becoming apparent until after the shipment has gone forward. Accordingly many of the boxes will break open in the freight cars or trucks, and valuable merchandise may thus be damaged or lost. The results from improper moistening of the tape are thus more far reaching than may be imagined.

To seal a shipping case safely, the complete surface of the tape should be moistened with an unbroken film of water in sufficient quantity to render the tape tacky rather than slippery. In order to apply such a film of water to a rapidly moving tape, it is necessary to supply a considerable but controlled amount of water. The most successful method which has been found for such application involves the use of an inverted brush which stands in a reservoir and feeds the water upward by capillary attraction. A pressure plate which is usually pivoted and adjustably weighted, presses the tape upon the tips of the brush bristles and also serves to maintain a film of water between itself and the tips of the bristles when no tape is passing over the brush. This film of water prevents the bristles from getting dry and keeps the machine at all times in condition for instant use.

The use of a single inverted brush has not been found wholly effective, however, for the

2

moistening of long lengths of rapidly moving tape. Accordingly two or more brushes arranged in tandem are preferably provided, as set forth in Patent No. 1,962,720. The use of a plurality of brushes is superior to a single brush for several reasons. In the case of a single brush the passage of the tape thereover is often so rapid that the water film tears apart into streaks instead of being applied continuously over the gummed surface. With tandem brushes the surface is brushed over twice so that a film which may be applied in streaks by the first brush is smoothly spread over the glue by the second brush. Multiple brushes are also more effective in raising the water from the reservoir by capillary attraction, because two brushes will have almost double the exposed surface of a single brush, even though the single brush were made the thickness of the two brushes combined. In like manner a combination of three spaced brushes will give approximately three times the water feeding capacity.

The proper use of multiple brushes, however, presents a number of problems not encountered in the use of a one brush moistener of the push-feed type. For example, in this type of dispenser a pivoted pressure plate is preferably used which is pivoted above the tank at its edge nearest to the shear on a fixed pivot, so that irrespective of the degree of pivoting, it is always in alignment with the shear at the pivoted edge so as to form a mouth of fixed location into which the leading end of the tape will enter and be guided over the brush tips. Gravity is relied upon to keep the pressure plate in contact with the water film over the top of the brush or brushes. In the case of a single brush, this action is simple even though the brush will bend when wet. When two or three brushes are used, however, with a pressure plate which gradually drops as the wet brushes bend after months of use, it has been found that contact between one of the brushes and the plate is often broken or partly broken. That is, either the entire tip of one brush or part of the tip no longer contacts the tape or the pressure plate. This breaking of contact may take place with two of the brushes when three are used in tandem. This prevents the brushes from functioning in the intended manner, and results in inferior moistening of the tape.

Another difficulty which has been encountered with multiple brush moistening units is that the brushes tend to come closely in contact with each other, thus shutting off the flow of tank water into the brush over the areas of contact.

Thus one of the important advantages of multiple brushes is lost. For example, in the case of a two brush combination, the access of water to the two adjacent brush faces is stopped, so that the brushes will feed only about one-half as much water as before.

The above troubles are due primarily to misalignment of the brushes; first, in relation to each other and second, in relation to the pressure plate. This misalignment, it has been found, may be caused by a number of conditions all of which occur only after the dispenser has been sold to a customer, and has been in use for a period of perhaps months. Furthermore, the ill effects of the improper operation of the moistener are usually not discovered by the customer until a number of improperly sealed shipping cases have broken open and valuable merchandise damaged or lost.

Among the conditions leading to improper action of the multiple brush are the following:

1. Since brush ferrules expand because of the gradual swelling of the cement in the ferrule, the space for each brush on the tank floor or on any rib supporting a brush must be considerably greater than the thickness of the ferrule when the brush is new. This allows the brushes to shift too close to each other.

2. While any two brushes are apt to touch at the tips when new, they touch over a much greater area after they have become bent. Thus water absorption is reduced.

3. After long constant use the thousands or even millions of feet of tape passing over the brushes grind down the bristles ends until they are much shorter than they were originally. The rear brush, nearest the pivot of the pressure plate, wears down faster than the forward brush because the weight (leverage) from on top is greater than on the forward brush.

In an effort to correct these conditions, the operator may, in replacing the brush after the periodic washing, transpose the brushes so that the short one is put where the long one was and vice versa. The long brush then holds the pressure plate up so that it is partly or wholly out of contact with the tip of the shorter brush resulting in poor moistening. Sometimes the rear brush may have been worn so short as to require a new one in its place, while the front brush may have worn down perhaps only half as much. In such instances the new brush will hold the pressure plate partly or wholly out of contact with the worn brush.

Another difficulty which has been met with is that when the worn brush is replaced, a brush of a different character of bristle may have been substituted. This has been particularly the case since the war, when Chinese bristles, considered the best for tape moistening, have been scarce and brushes with substitute bristles such as horse hair have been used. The horse hair brush stays thicker and stiffer when wet than the China bristle brush. When a dispenser originally equipped with horse hair brushes is fitted with a China bristle replacement brush (or vice versa), the misalignment of the two brushes causes bad moistening.

It is also true that any brush used in a tape moistener becomes useless for moistening tape when only a portion of the bristles, perhaps only $\frac{1}{6}$ or $\frac{1}{5}$ wears down. When this amount of wear has taken place the tape is apt to clog or buckle. Accordingly the brush has to be replaced, which represents a considerable economic waste, in view

of the greatly increased cost of brushes in the last few years.

It is an object of the present invention to overcome the difficulties above named, some features of the invention being applicable to single brush units as well as to multiple brushes.

One object of the invention which is applicable to both single and multiple type brushes is the provision of a brush having a ferrule end of adjustable length, so that as the brush wears it can in effect be lengthened sufficiently to maintain the tip of the brush in proper relation to the pressure plate throughout a long period of use. This feature of the invention is applicable to all types of brush feed moisteners including the so-called "pull and tear" moisteners as well as the "push feed" type of dispenser.

In the case of multiple brush moistening units, the principal object of the present invention is to provide means for maintaining the brushes at all times in proper alignment with each other and with the pressure plate. This is accomplished, first by providing means for keeping the adjacent brushes properly spaced from each other so that the outer surfaces of the brush are in contact at all sides of the brush with the water in the tank, thereby providing the maximum feed of water by the brushes. Secondly, means are provided to raise and lower each brush independently of the other brush or brushes, so that if any brush or brushes wear, they may be maintained in their proper relationship to the pressure plate, thereby assuring correct application of moisture to the tape. By providing such independent adjustment, the useful life of each brush may be trebled or quadrupled. Furthermore it is possible to replace any one brush with a new brush, whether of the same character of bristle or of a different bristle, while still securing the completely satisfactory operation of the multiple brush unit.

In preferred embodiments of the invention, the adjustment may be made without withdrawing the brush from the tank and under conditions in which the operator can observe the adjustment of the brush with reference to the pressure plate while the adjustment is being made. He can thus quickly bring the brush to correct position.

Further objects and advantages of the invention will appear in the course of the following detailed description of certain preferred embodiments of the same.

In the accompanying drawings:

Figure 1 is a side elevation showing part of a tape dispenser with the water reservoir therein shown in vertical longitudinal section, one form of adjustable brush mount being illustrated.

Figure 2 is a vertical transverse section on line 2-2 of Fig. 1.

Figure 3 is a plan view of the water reservoir and brushes with the pressure plate removed.

Figure 4 is a fragmentary vertical section on line 4-4 of Fig. 2.

Figure 5 is a longitudinal vertical section of a water reservoir showing a modified adjustable mount for a plurality of brushes.

Figure 6 is a similar view showing another modified brush adjustment means.

Figure 7 is a transverse vertical section on line 7-7 of Fig. 6.

Figure 8 is a vertical longitudinal section showing a water reservoir with one form of adjustable brush mounted therein.

Figure 9 is a side elevation of the adjustable brush shown in Fig. 8.

Figure 10 is a perspective view of another form of adjustable brush.

In the form of invention shown in Figs. 1, 2, 3 and 4, a two brush moistening unit is illustrated in which means are provided for adjusting the elevation of one of the brushes. This permits one of the brushes to be raised and lowered as desired, and where necessary the brushes can be interchanged or one of the brushes can be replaced, and the proper adjustment effected. The construction is illustrated in connection with the conventional push feed dispenser in which the tape 20 is fed from a supply roll 22 by means of rollers 24 and 26, the latter being driven through speed multiplying gearing (not shown) by means of a crank 28. Such dispensers are well known and are capable of feeding quite long lengths of tape at high speeds. The tape passes over a fixed guide plate 30, past a shear cutter indicated generally at 32 and under a pressure plate 34 provided with a weight 36 which is desirably adjustable towards and from the pivot 38, upon which the pressure plate is mounted so as to vary the pressure of the plate upon the tips of the brushes. The pressure plate is mounted over a water reservoir 42 having a brush chamber 44 and a laterally projecting feed chamber 46 to which water is supplied from an inverted reservoir. The reservoir is shown as in the form of a bottle having a neck 50 projecting into the chamber 46 and resting upon an inclined supporting plate 52 on which it is held in adjustable position by means of a clip 54 having a bent ear 56 adapted to engage in any of a number of notches 58 in the plate 52. The adjustment of the mouth of the bottle determines the level of the water in the tank, and this level will be maintained as long as there is water in the bottle.

In the construction shown two brushes are illustrated, the front brush 60 having its ferrule end 62 resting in an inclined position upon the bottom of the tank and spaced from the front of the tank by ribs 65, the upper part of the brush resting against the lip 66 at the front of the tank. The second brush 68 has its lower ferrule end 70 spaced away from the butt end of the first brush, the tip of the brush resting against the tip of the first brush. The lower parts of the brushes which are submerged in the water in the tank are spaced apart so that free access of the water to both sides of both brushes is obtained.

The ferrule end 70 of the brush 68 is supported on an adjustable base plate 72 which is fixed to a rotatable pintle 74. A simple and effective mounting for this pintle is illustrated, such mounting comprising the plate 76 riveted to the wall 78 of the tank. The plate 76 has its lower edge bent into the form of a bearing socket 80 through which the pintle 74 passes. The plate 72 is provided with a slot 82 for the reception of the plate 76. One end of the pintle 74 extends into the feed chamber 46 of the tank and is bent and flattened to provide a laterally projecting arm 84. An adjusting screw 86 screws through a threaded opening in this arm, the lower end of the screw bearing on the bottom of a shallow recess 88 in the bottom of the tank chamber. A spring 90 is preferably provided, one leg 92 of which bears against the front wall 94 of the tank chamber 46; while the rear leg 96 is formed into a hooked portion pressing rearwardly against screw 86 so as to urge the latter in a direction to hold the screw tip against the bottom of the recess 88. With this construction it will be seen that by backing off the screw, arm 80 will be permitted to rotate

downwardly, thus lifting the base plate 72 and raising the brush supported thereby. The position of the brush may thus be accurately adjusted by turning the screw 86 and such adjustment will be maintained until a new adjustment is required by the changed condition of the brush. It will be seen that the screw is so located in the feed chamber 46, which projects at one side of the machine, that it may be readily reached by a screwdriver and adjustment made without dismantling any part of the dispenser. Furthermore, the operator may observe the position of the tip of the brush with reference to the pressure plate and thereby secure accurate adjustment under actual conditions of use.

Fig. 5 shows a modified construction in which the brushes are mounted on a tilting base so that a differential adjustment of the brushes is possible. In this way the contact of these brushes with the pressure plate may be equalized. This form of the invention is shown in a three brush unit, although it is not so limited. The base of each brush is mounted in a separate brush holding cup or channel 100, the three channels being fixed on a plate 102 provided with downly turned flanges 104 which are mounted on a pivot pin 106. The pivot pin is supported by a bracket 108 secured to the bottom of the cup. A spring 110 urges the base in one direction and at the other side of the base is an adjusting screw 112. The adjusting screw is preferably located near one end of the tank so that it may be reached by a screwdriver passed down into the tank at the side of the brushes. By changing an adjustment 15 of the base and interchanging the brushes as may be required, an equalized pressure of the brushes upon the tape and pressure plate may be secured.

Figure 5 also shows the use of brush spacing pins 113 mounted near the top of the tank transversely thereof, and located between the brushes so as to hold the tips separated.

Another modified arrangement for adjusting the brushes is shown in Figs. 6 and 7. This construction is illustrated in connection with a three brush unit, but obviously might be used with a unit of one or more brushes. In this construction each of the brushes is shown as attached to carrier arm 114 which projects from a block 116. The block 116 has two vertical holes therein, one of which 118 has a smooth bore therethrough, and slides on a guide pin 120. The other hole in the block 122 is internally threaded and through this hole screws an adjusting screw 124 which may be provided with a knurled head 126. The lower end of the screw 124 is rotatably mounted in an unthreaded bore 128 in a boss 130 forming part of the tank bottom. As shown in Fig. 7 the adjusting screw is located at one side of the brushes so that it may be readily rotated without requiring removal of the brushes or pressure plate. With the construction shown each of the brushes may be individually adjusted and the adjustment of the tips of the brushes 20 with relation to the pressure plate may be observed while the operation is being carried out, so that quick and accurate adjustment is possible.

Figures 8 and 9 show a brush having adjusting means on its butt end so that the brush may be raised or lowered in the tank. This is particularly useful in case the brush is worn down, as it may be raised to a position where it will function properly, and thereby its useful life may be prolonged. The figures show a tank containing a single adjustable brush, but obviously

brushes of this type might be used in multiple brush units if desired. In the construction shown the tank 130 is provided with ribs 132 and 134 forming a channel for the reception of the brush ferrule 136. Screwing into the butt of the brush are screws 138, which may be backed off, as indicated in dotted lines in Fig. 9. By properly adjusting the screws the tip of the brush may be brought to proper elevation.

Figure 10 shows a modified construction of brush having an adjustable foot. In this construction the foot comprises a bent plate 140, the vertical side of which is provided with slots 142 through which press screws 144 by which the plate may be clamped in adjusted position on the side of the brush ferrule. At the bottom of the plate 140 is a horizontal flange 146, adapted to rest on the bottom of the tank.

While certain preferred embodiments of the invention have been illustrated and described in detail, it is to be understood that changes may be made therein and the invention embodied in other structures. It is not, therefore, the intention to limit the patent to the specific constructions illustrated, but to cover the invention broadly in whatever form its principle may be utilized.

What I claim is:

1. In a tape dispenser, a tape moistener comprising a water tank, a pressure plate mounted above the same and a plurality of inverted brushes mounted in tandem in said tank with their tips projecting upwardly into engagement with said pressure plate, and means for changing the vertical adjustment of at least one of said brushes with relation to said pressure plate and to another of said brushes, said means including a supporting plate upon which one of said brushes rests, a pintle to which said supporting plate is fixed and means for turning said pintle and holding it in adjusted position.

2. In a tape dispenser, a tape moistener comprising a water tank, a pressure plate mounted above the same and a plurality of inverted brushes mounted in tandem in said tank with their tips projecting upwardly into engagement with said pressure plate, and means for changing the vertical adjustment of at least one of said brushes with relation to said pressure plate and to another of said brushes, said means including a supporting plate upon which one of said brushes rests, a pintle to which said supporting plate is fixed, an arm on said pintle and an adjusting screw on said arm for turning said pintle and holding it in adjusted position.

3. In a tape dispenser, a tape moistener comprising a water tank, a pressure plate mounted above the same and a plurality of inverted brushes mounted in tandem in said tank with their tips projecting upwardly into engagement with said pressure plate, and means for changing the vertical adjustment of at least one of said brushes with relation to said pressure plate and to another of said brushes, said means including a supporting plate upon which one of said brushes rests, a pintle to which said supporting plate is fixed, an arm at one end of said pintle and an adjusting screw on said arm for turning said pintle and holding it in adjusted position, said tank having a laterally projecting filling chamber, the end of said pintle projecting into said filling chamber, said adjusting screw being located in said chamber where it may be reached for adjustment without disturbing the brushes or pressure plate.

4. In a tape dispenser, a moistening unit comprising a tank, a pressure plate mounted above the tank, an adjustable support mounted in the tank, a plurality of individual brush holders mounted on the support each holding one of a plurality of inverted brushes arranged in tandem, means for mounting said support for pivotal movement about a horizontal axis, and an adjusting device for adjusting the position of said support about said axis, said adjusting device including an actuating element located near one end of the tank at the side of the brushes so that it may be reached for actuation at the side of the brushes without displacement of the brushes from the tank or of the tape from its position between the pressure plate and brushes.

5. In a tape dispenser, tape moistening means comprising a tank, a pressure plate mounted over the tank, a portion of the tank extending laterally of said pressure plate, an inverted brush mounted in said tank having its tip adapted to engage said pressure plate, a vertical guide mounted in the laterally extended part of the tank, a block mounted to slide on said guide, an arm carried by said block extended across the lower part of the tank and secured to the butt of the brush, said block having a threaded hole therethrough and an adjusting screw screwing through said hole, said adjusting screw having a head projecting at one side of the pressure plate where it may be grasped for rotation without interference from the brush or pressure plate.

6. In a tape dispenser, a moistening unit comprising a tank, a pivoted pressure plate mounted above the tank, said tank having an extension extending beyond the side of the pressure plate, a plurality of individual brush holders mounted in said tank, each of said brush holders having a portion extending into said lateral extension, an adjusting screw for each of said holders mounted in said lateral extension, each adjusting screw having a head portion at one side of said pressure plate where it can be reached for turning the screw without interference from the pressure plate, and an inverted brush carried by each of said brush holders.

7. In a tape dispenser, a moistening unit comprising a tank, a pivoted pressure plate mounted above the tank, a plurality of inverted brushes mounted in tandem in said tank, means for spacing the upper parts of said brushes and means for relatively adjusting the elevations of said brushes.

8. In a gummed tape dispenser, tape feeding means for feeding the tape, and a tape moistening couple through which the tape is passed by the tape feeding means, said tape moistening couple comprising a tank and a plurality of inverted brushes mounted in tandem in said tank with their tips projecting upwardly into a position for engagement with the tape fed by the tape feeding means, and a single presser element movably mounted above said brushes, said presser element and brushes jointly forming a tape receiving mouth, said presser element contacting with both of said brushes in forming a single tape path past the brushes, supporting means for said presser element for supporting the same adjacent to the tips of the brushes so that the mouth between the presser element and tips of the brushes is always in alignment with the path of tape movement to receive the end of the advancing tape, said brushes and presser element jointly forming self-adjusting means for maintaining the gummed side of the tape in en-

gagement with the tips of the brushes when the tape is present between them, and for maintaining the brushes and presser element in contact with one another to maintain a film of water at the brush tips when no tape is present between them, and means for changing the vertical adjustment of at least one of said brushes in relation to the presser element and to another of said brushes said means including an actuating member located laterally out of line with the tape path so that it may be reached without displacing the tape from its path over the brushes, said brush adjusting means being operable without removing the brushes from the tank.

9. In a gummed tape dispenser, a tape guiding means for guiding tape in a predetermined path, tape feeding means for advancing the tape through said tape guiding means, a water tank mounted in advance of said tape guiding means, a plurality of inverted brushes mounted in tandem in said tank with their tips projecting upward into a position to engage with tape fed from said tape guiding means, a presser plate mounted for pivotal movement about an axis near the forward end of said tape guiding means, said presser plate extending beyond the end of said tape guiding means and resting by gravity on the tips of said brushes or upon the tape when the same is fed between the plate and the tips of the brushes, and means located in the tank for changing the vertical adjustment of at least one of said brushes with relation to said presser plate and to another of said brushes, said adjustment means being operable while the brushes are in position in the tank, said adjusting means including an actuating member located laterally out of line with the tape path so that it may be reached without displacing the tape from its path over the brushes.

10. In a gummed tape dispenser, a tape guiding means for guiding tape in a predetermined path, tape feeding means for advancing the tape through said tape guiding means, a water tank mounted in advance of said tape guiding means, a plurality of inverted brushes mounted in tandem in said tank with their tips projecting upward into a position to engage with tape fed from said tape guiding means, a presser plate mounted for pivotal movement about an axis near the forward end of said tape guiding means,

5 said presser plate extending beyond the end of said tape guiding means and resting by gravity on the tips of said brushes or upon the tape when the same is fed between the plate and the tips of the brushes, a brush lifter in the tank engaging the butt of at least one brush, and means operable from outside of the tank without removal of the brushes for adjusting said brush lifter, said means including an actuating member 10 located laterally out of line with the tape path so that it may be reached without displacing the tape from its path over the brushes.

11. In a gummed tape dispenser, a tape guiding means for guiding tape in a predetermined path, tape feeding means for advancing the tape through said tape guiding means, a water tank mounted in advance of said tape guiding means, said tank comprising a brush chamber and a feed chamber projecting laterally from said brush chamber and communicating therewith, a plurality of inverted brushes mounted in tandem in said tank with their tips projecting upward into a position to engage with tape fed from said tape guiding means, a presser plate mounted for pivotal movement about an axis near the forward end of said tape guiding means, said presser plate extending beyond the end of said tape guiding means and resting by gravity on the tips of said brushes or upon the tape when the same is fed between the plate and the tips of the brushes, a brush lifter in the brush chamber of said tank engaging at least one of said brushes, and adjusting means for said brush lifter including a part extending into the feed chamber of said tank and an adjusting element located in said feed chamber which may be reached for adjustment through said feed chamber so that adjustments may be made without removal of the brushes from the tank.
